(57) **CLAIM**

The ornamental design for an earphone case, as shown and described.

DESCRIPTION

FIG. 1 is a top, front, and right perspective view of the earphone case showing our new design, shown in a closed configuration.

FIG. 2 is a bottom, rear, and left perspective view of the earphone case of FIG. 1, shown in the closed configuration. FIG. 3 is a front view of the earphone case of FIG. 1, shown in the closed configuration.

FIG. 4 is a rear view of the earphone case of FIG. 1, shown in the closed configuration.

FIG. 5 is a left side view of the earphone case of FIG. 1, shown in the closed configuration.

FIG. 6 is a right side view of the earphone case of FIG. 1, shown in the closed configuration.

FIG. 7 is a top view of the earphone case of FIG. 1, shown in the closed configuration.

FIG. 8 is a bottom view of the earphone case of FIG. 1, shown in the closed configuration.

FIG. 9 is a top, front, and right perspective view of the earphone case of FIG. 1, shown in an open configuration. FIG. 10 is a bottom, rear, and left perspective view of the earphone case of FIG. 1, shown in the open configuration. FIG. 11 is a front view of the earphone case of FIG. 1, shown in the open configuration.

FIG. 12 is a rear view of the earphone case of FIG. 1, shown in the open configuration.

(Continued)

FIG. 13 is a left side view of the earphone case of FIG. 1, shown in the open configuration.

FIG. 14 is a right side view of the earphone case of FIG. 1, shown in the open configuration.

FIG. 15 is a top view of the earphone case of FIG. 1, shown in the open configuration; and,

FIG. 16 is a bottom view of the earphone case of FIG. 1, shown in the open configuration.

The ornamental design which is claimed is shown in solid lines in the drawings. The broken line showing in FIGS.

1-16 illustrates the environment, which forms no part of the claimed design. The shade lines in the figures show contour, not surface ornamentation and form no part of the claimed design.

1 Claim, 6 Drawing Sheets
